(57) **CLAIM**

The ornamental design for a recycling bin, as shown and described.

DESCRIPTION

FIG. 1 is a perspective view of a recycling bin showing a first embodiment of my new design;

FIG. 2 is a front elevational view of the recycling bin of FIG. 1;

FIG. 3 is a back elevational view of the recycling bin of FIG. 1;

FIG. 4 is a left side elevational view of the recycling bin of FIG. 1, the right side elevational view being the same as the left side view;

FIG. 5 is a top plan view of the recycling bin of FIG. 1;

FIG. 6 is a bottom plan view of the recycling bin of FIG. 1;

FIG. 7 is a perspective view of a recycling bin showing a second embodiment of my new design;

FIG. 8 is a front elevational view of the recycling bin of FIG. 7;

FIG. 9 is a back elevational view of the recycling bin of FIG. 7;

FIG. 10 is a left side elevational view of the recycling bin of FIG. 7, the right side elevational view being the same as the left side view;

FIG. 11 is a top plan view of the recycling bin of FIG. 7; and, FIG. 12 is a bottom plan view of the recycling bin of FIG. 7.

The recycling bin of FIGS. 1–6 is shown in the views with a portion broken-away to indicate indeterminate width.

The recycling bin of FIGS. 7–12 is shown in the views with portions broken-away to indicate indeterminate width.
